UNITED STATES PATENT OFFICE.

ARTHUR KIRK, OF SHARPSBURG, PENNSYLVANIA.

MOVABLE DAM.

SPECIFICATION forming part of Letters Patent No. 268,411, dated December 5, 1882.

Application filed May 31, 1881. (No model.)

To all whom it may concern:

Be it known that I, ARTHUR KIRK, of Sharpsburg, in the county of Allegheny and State of Pennsylvania, have invented a new and useful Improvement in Movable Dams; and I do hereby declare the following to be a full, clear, and exact description thereof.

My invention relates to improvements in the construction of movable dams and locks, where-
10 by they are stronger, safer, more durable, and more easily operated than those heretofore in use. By my improvements defects heretofore existing in the old bear-trap plan are overcome.

My invention consists, first, in constructing
15 the foundation with several floors having intervening spaces which are divided into compartments by partitions of any desired height formed by boards laid alternately at an angle to each other, so arranged as to cross at intervals, 20 and then fitting the spaces between the boards with cement and the compartments with sand, gravel, stone, or other suitable material; second, in extending the ends of the top floor several feet beyond the foundation to protect the latter
25 from percolation or wash of the water, which undercuts the foundation; third, of an improved dam-gate consisting of a double journal or pintle bolted to one part, with each journal working in one end of a double-ended sleeve on the other
30 part, the said parts being respectively bolted to the gate or foundation, and each pintle works in the adjoining ends of two sleeves, so that as long a hinge as is desired is made by simply adding duplicates of the parts named;

35 fourth, of a rising gate or gates provided with a telescoping joint, which, permitting a limited movement, will enable the gates to accommodate themselves to any unequal settling of the foundation; fifth, of an open sluice, water-way,
40 or tail-race so arranged relatively to the dam that the water which is not required to support the leaves will escape, and so relieve the dam of all unnecessary pressure; sixth, in supports or props hinged to the foundation, under
45 the gates, for use in supporting the gates in case of repairs; seventh, in operating the wickets by levers connected to pistons actuated by hydraulic, air, or steam pressure supplied from and controlled at a common point; eighth, in
50 a moving signal connected to the rising gate, and so arranged as to indicate the elevation of

the dam; ninth, in use of wooden screws in those parts exposed to water; and, finally, in details of construction hereinafter set forth.

To enable others skilled in the art to make 55 and use my invention, I will now describe the same by reference to the accompanying drawings, (three sheets,) in which—

Figure 1 is a vertical cross-section of the dam and foundation, the gates being down. Fig. 2 60 is a like view of the gates when up. Fig. 3 is a detail view, illustrating the construction of the foundation. Fig. 4 is a view of one form of the relieving tail-race. Fig. 5 is a section of a portion of one of the gates, showing the 65 telescoping joint and the water-tight joint between the end of the dam and the abutment. Fig. 6 shows the use of the wooden screws in the construction of the gates. Figs. 7 and 8 are sectional views of the gate-hinge. Fig. 9 70 illustrates the manner of operating the wickets from one point by steam, air, gaseous, or water pressure. Fig. 10 is a view of the signaling apparatus.

Like letters of reference indicate like parts 75 in each.

The foundation 1, the gates 2 and 3, and lower wall, 4, are made of boards or planks of wood (or sheets of iron) in longitudinal and transverse courses 5 and 6, of irregular length 80 and width, so that the boards of each longitudinal or transverse course shall break joint with those of other longitudinal or transverse courses. This construction does away with the necessity of preparing the timber to any particular size or shape, and makes a stronger and more compact structure than can be obtained in the use of solid cut timber.

The foundation 1 is constructed of several distinct floors, 7, 8, and 9. The first floor, 7, 90 rests on the transverse timbers 10, and is composed of three or more longitudinal and transverse courses of boards, 5 and 6. Above the floor 7 are a number of compartments, 11, of any desired size, formed by partitions 12, made 95 of boards or planks 13 14, Fig. 3, crossing each other at intervals and piled to any desired height to form pens. The spaces 15 left between the parallel boards by the lateral ones are filled or closed with cement to make them 100 water-tight, and then the compartments 11 are filled with stones, gravel, sand, or other heavy

material. The second floor, 8, is similar in construction to floor 7, and covers the compartments 11. Above it other compartments, 16, similar to compartments 11, are formed by building the partitions 12 up to the desired height. The spaces 15 are then closed with cement and the compartments filled with stone or other suitable material, the same as compartments 11. The third or top floor, 9, is made in the same way as the floors 7 and 8, but preferably thicker, and with the ends extended beyond the substructure, up and down stream, as at 61, to prevent the foundation being damaged by the percolation or reaction of the water in 15 to and through it, which might occur if the wash or waves struck immediately against the substructure.

The gates 2 and 3 are constructed, as described, of longitudinal and transverse courses 20 of boards or planks 5 and 6, which break joint with each other. These gates are of any desirable length, being made long enough to extend across the stream. This is possible by reason of the boards or planks of which they 25 are formed overlapping each other, so that, in fact, there need be no limit to the length of the dam. The gates are hinged so that the upper one, 2, overlaps the end of the lower one, 3, whether open or closed. In order to relieve 30 the friction of the lower gate on the upper one in opening and closing, I provide the lower one, 3, with a friction roller or rollers, 17, at its outer upper edge. The gate 3 is hinged to the foundation 1, and when closed lies flat near 35 the floor 9. The gate 2 is hinged to a wall, 4, at such a height that when closed it shall be horizontal, or nearly so, and rest upon the gate 3. Under the gates, and hinged to the foundation at 18, are pivoted supports 19, used for suspending the gates in an open position to facilitate 40 repairs, as shown in Fig. 2. When not in use the supports 19 are laid flat on the floor 9, as shown in Fig. 1.

The hinge, Figs. 7 and 8, is of novel construction. The eye 20 is bolted to the foundation. The pintle 21 is bolted to the gate. It consists of a plate, 22, by which it is bolted to the gate or gates, a central web, 23, and a pintle, 21, extending both ways from the central web, 23, forming two pintles, 24. Each pintle 24 enters the recess 25 of one end of the eye or socket piece 20. The socket-piece 20 is like a section of a tube having a central division-wall, so as to strengthen and divide it into two parts. 55 The pintles 24 enter the adjacent ends 25 of each of two socket-pieces, 20, and the socket-pieces are secured firmly in place by bolts 26 and the pintle pieces by bolts 27. The upper side is cut away, as at 28, to provide room for 60 the web 23, while below the edges meet. On the under side are projections 29, which are let into the foundation. This hinge is strong, cheap, and durable, and the parts fit together so as to be water-tight. By simply adding 65 other pieces it can be extended to any desirable length. I prefer to make the meeting

edges serrated or of equivalent form, so that the water which enters between them is caused to act as a packing to the joint and seal it.

The gate or gates 2 and 3 are provided with 70 telescoping section or joint 30, (see Fig. 5,) which is formed by cutting the longitudinal courses of timber off with an even edge, as at 31, across the gate, and the transverse courses in like manner, as at 32, back of the ends 31 of 75 the longitudinal timbers. The part between the two cuts 31 and 32 is not bolted, so that the interleaved ends are free to move on each other, and in case of the settling of the foundation 1 at any point the gate, parting slightly, 80 as at 30, is able to accommodate itself thereto. Heretofore the rigid structure of the gates caused them to stand straight, and not follow the foundation in case of its sinking. The joint 30 is water-tight, and is simple in form 85 and construction, easy and effective in operation.

At the ends of the dam I form a water-tight joint between the gate or gates and the stationary abutment 33 by means of a movable 90 timber or piece, 34, running transversely of the gate in a recess on its edge. Back of the timber 34 is a recess or channel, 35, which communicates to the water above by a large inlet-opening, 36, at the upper end, and has a 95 smaller discharge-opening, 37, at the lower end. The water from above, entering the channel 35 by the large opening 36, causes the piece 34 to be pressed out against the wall 33 and form a tight joint therewith. The water escapes from the channel 35 by the small exit 37. There is little friction between the piece 34 and the wall 33, because as soon as the gate 2 begins to descend the pressure on 34 is relieved and it falls back in the recess 35. The 105 discharge 37 is to prevent the collection of sediment in the recess 35, which might prevent the working of the piece 34.

In the end wall of the dam I make an open sluice, water-way, or tail-race, 38, Fig. 2, at 110 such height as will permit all water which is not required to sustain the gates to escape from under them. When the gates are down, as in the position shown in Fig. 1, the water is admitted by the wickets under them. This raises 115 and floats them up until they reach the position shown by Fig. 2. By that time the water having reached the sluice 38, which passes through the wall around the end of the gate, will flow freely through, sustaining the gates at that 120 level.

A modified construction of the sluice 38 is shown by Fig. 4, where the outlet 39 in the wall is below the level of the water, the latter passing through the outlet 39 into a forebay or 125 well, 40, and thence over the bridge 41.

If desired, the discharge-opening may be controlled by a valve operated by a float.

It is apparent that the form, place, and details of construction of the sluice for relieving 130 the gates from excessive pressure below can be varied by the skilled constructor; but in all

cases an open channel will be necessary when the water has reached a certain height or pressure under the gates.

I bring the operation and control of the wickets for admitting and discharging the water to and from the dam to one spot and put it under the control of one man. To the shaft of each wicket 42, Fig. 9, I attach a lever, 43, the other end of which is connected to a piston, 44, working in a cylinder, 45, from which a pipe, 46, leads to the operator's stand 47. The pipe 46 is connected to a compressed-air tank, 48, and is controlled by a suitable cock, 49. All of the wickets are similarly connected. The operator, having the cocks all within reach, can open and close the wickets at pleasure and with uniformity. I thus save in labor and time and secure great efficiency of operation. I prefer to use a three-way cock and a vacuum-cylinder, 50, for relieving the pressure on the pistons 44, as thereby the action is more prompt. I can use steam, water or other liquid or gaseous medium for actuating the pistons by simply adapting the apparatus thereto.

I have also devised an automatic signal which shall show the exact height and position of the dam. On the end wall I erect a frame of posts, 51 and 52, and cross-piece 53. A stationary lantern, 54, flag, or other signal is placed on the cross-piece 53 at a suitable point. A rope or chain, 56, is fastened to the outer end of the rising gate 2, and passes up over pulleys 57, placed at the corners of the framing, and is provided with a weight, 58, at the other end. A lantern, 59, or other signal is fastened to the chain 56 in such relation to the signal 54 that upon the rising or falling of the gate 2 it shall change its relative position to the signal 54, and thereby clearly indicate the exact position of the gate or dam. The operation of the signal by the moving of the gate itself insures absolute accuracy and great consequent safety.

The planking of the various parts of the foundations and gates which are exposed to water is fastened by wooden screw-bolts 60, Fig. 6, the threads of the male screw being preferably of a quicker pitch than that of the female screw, so as to force the parts tightly together. The bolts are made of dry or partially-dried wood, and when exposed to the water will swell and make a very tight fastening.

I am aware that the crib-work has heretofore been constructed of timber upon a float or floor composed of several courses of dressed planking or timber, and also that guards and a horizontal apron have been arranged on the downstream side of a dam to arrest the silt and detritus and prevent the undermining of the dam by the backwash of the water, and do not herein claim the same; but

What I claim as my invention, and desire to secure by Letters Patent, is—

1. A dam-foundation constructed of several 65 floors having intervening spaces divided into compartments by partitions formed of boards laid to cross each other at intervals and cemented between, and the compartments filled with stone or other suitable substance, substantially as and for the purposes described. 70

2. A dam-foundation composed of two or more floors, the space between the floors being filled with stone or like material, and the upper floor extending beyond the substructure to prevent the wash and percolation of the water from undercutting the foundation, substantially as specified. 75

3. A dam-gate hinge consisting of a double journal or pintle bolted to one part, working 80 in the adjacent ends of a double-ended sleeve secured to the other part on each side of it, said sleeve having a central partition to strengthen it and separate the two ends of the adjacent pintles, substantially as and for the purposes 85 described.

4. A rising dam gate or gates provided with a telescoping joint, substantially as and for the purposes described.

5. The combination, with a dam-gate and 90 its abutment, of a movable timber-piece running transversely of the gate, and means, substantially as specified, for exerting a yielding pressure on the movable timber-piece, whereby a tight joint between the abutment and 95 gate is obtained, substantially as and for the purpose specified.

6. A bear-trap dam having a relieving or open sluice extending from under the gates, so as to relieve them from unnecessary pressure, substantially as and for the purposes described. 100

7. A rising dam provided with hinged supports under the gates, substantially as and for the purposes described. 105

8. The combination of the wicket-stems with pistons connected thereto, cylinders, pipes leading to a common central office, and controlling-valves, whereby all the wickets may be operated by liquid or fluid pressure from a 110 common center, substantially as and for the purposes described.

9. The combination of a rising dam with a signal chain or cord attached thereto, and a lantern or other signal to indicate the condition of the dam by its change of position, substantially as and for the purposes described. 115

10. A wooden dam or foundation the courses of which are fastened by wooden screw-bolts, substantially as and for the purposes described. 120

In testimony whereof I have hereunto set my hand.

ARTHUR KIRK.
